Fredrick Cluskey,

By his Attorney

Patrick O'Farrell.

UNITED STATES PATENT OFFICE.

FREDRICK CLUSKEY, OF LAKENAN, MISSOURI.

TRUSS.

SPECIFICATION forming part of Letters Patent No. 430,924, dated June 24, 1890.

Application filed September 12, 1889. Serial No. 323,747. (No model.)

To all whom it may concern:

Be it known that I, FREDRICK CLUSKEY, a citizen of the United States of America, residing at Lakenan, in the county of Shelby 5 and State of Missouri, have invented certain new and useful Improvements in Hernia-Trusses, of which the following is a specification, reference being had therein to the accompanying drawings.

This invention pertains to a certain new and useful improved hernia-truss, having for its object the provision of new and improved highly-efficient means for holding up or supporting the injured or swollen parts, resulting in a cure.

The invention consists of a two-part sectional belt united at its rear by a buckle and strap, and having a downwardly-extending rigidly-secured pad-block secured to one of 20 the sections and provided with a removable button, and a flexible movable connection between the front ends of said sections, all constructed and arranged, substantially as hereininafter fully set forth, and particularly pointed out in the claims.

In the accompanying drawings, Figure 1 is a view in perspective of my improved truss. Fig. 2 is a cross-sectional view on the line $x-x$, Fig. 1. Fig. 3 is a detail view of the pad-block; and Fig. 4 is a cross-section on the line $y-y$, Fig. 3.

Referring to the drawings, A designates the belt composed of two sections a a' , united together at their rear ends by a strap a^2 and a buckle a^3 , said strap being passed through end loops of said sections. By means of the strap and buckle the belt can be drawn and held secure at any desired point.

B is the pad-block or support through a 40 keeper b , on the rear side of which is passed a rod b' , the same being adjustable and held fast at any desired point by a set-screw b^2 . The upper right angular end of this rod is passed through a second keeper C, rigidly 45 secured to one end of the belt, said rod being likewise held by a set-screw C', as shown. Thus the pad-block is capable of adjustment, and can be raised or lowered or moved in or out and firmly held at any point. In the inner face of this pad-block is a small groove or opening d , wherein fits the reduced por-

tion or lug d' of a button D, which is thereby firmly held in place.

D' is a pulley, having a bracket d movably secured on the extended end d' of section a' 55 of belt A. A strap D^2 is passed around this pulley, and its split ends are secured upon the set-screws b^2 and C'. In this manner a flexible or movable self-adjustable connection is secured between the front meeting ends of 60 the sections of the belt.

E is a double coil-spring, the extended ends of which are secured beneath turned-over edges e of one end of section a of belt A. The tendency of said spring is to force the 65 end of the section inward, and thus hold the pad-block firmly in place. The ends of this double spring are extended in opposite directions, and said springs being of strong tension the ends serve to force the front end of 70 belt-section a inward toward the body of the wearer.

The advantages of my invention will be apparent to those skilled in the art to which it appertains, and it will be particularly observed that the pad-blocks can be adjusted and rigidly secured at any desired point, and that the belt is free to move at its front portion so as to conform to any desired angle or position assumed by the wearer.

My invention is simple, cheap, and durable, and results in many cases in a rapid cure of the disability for which worn.

Another and important advantage of my invention is that the pad-block is capable of 85 being worn on either side. It will be understood that the button D does not move, but that the pad-block continuously follows the movement of the body. This is effected by the flexible connections between the front 90 ends of the sections of the belt.

I claim as my invention—

1. The herein-described improved hernia-truss, comprising the two-part or sectional belt, the sliding pulley secured to the front 95 end of one section of said belt, and the strap having its ends secured to the same end of the other section and passed around said pulley, substantially as set forth.

2. The herein-described improved hernia-truss, comprising the two-part or sectional belt having a rear connecting-strap and

buckle, the pad-block adjustably secured to the front end of one section of said belt, the movable or sliding pulley also secured to the front end of one of said sections, and the strap having its ends secured to the other section and passed around said pulley, forming the connection between the front ends of the belt, substantially as set forth.

3. The belt herein described, composed of
10 two sections flexibly connected together, one

of said sections having a coil-spring, the ends of which are secured under overlapping edges of said sections, substantially as set forth.

In testimony whereof I affix my signature in presence of two witnesses.

FREDRICK CLUSKEY.
